United States Patent Office

Des. 220,784

Patented May 18, 1971

220,784

SPOON OR SIMILAR ARTICLE OF FLATWARE

Robert King, Wallingford, Conn., assignor to International Silver Company, Meriden, Conn.

Filed June 8, 1970, Ser. No. 23,382

Term of patent 14 years

Int. Cl. D7—03

U.S. Cl. D54—12

FIG. 1

FIG. 2

FIG. 3

FIG. 4

FIG. 1 is a front elevational view of a spoon showing my new design;

FIG. 2 is a rear elevational view thereof;

FIG. 3 is a side elevational view thereof; and

FIG. 4 is a sectional view on an enlarged scale taken on lines 4—4 of FIG. 1.

The design is intended for use on sets comprising spoons, forks, knives and similar articles of flatware.

I claim:

The ornamental design for a spoon or similar article of flatware, substantially as shown and described.
